GAME BOARD

Roy V. De Voy, North Hollywood, Calif.

Application April 29, 1949, Serial No. 2,337

Term of patent 3½ years

(Cl. D34—5)

To all whom it may concern:

Be it known that I, Roy V. De Voy, a citizen of the United States of America, and a resident of the city of North Hollywood, in the county of Los Angeles and State of California, have invented a new, original, and ornamental Design for Game Board, of which the following is a specification, reference being had to the accompanying drawings, all of which form a part hereof.

In the drawings:

The sides of the game board not shown have substantially the same appearance as the sides shown in Figs. 2 and 3. The bottom of the game board is plain and unornamented.

Fig. 4 is partially broken away for convenience of illustration.

I claim:

The ornamental design for a game board, substantially as shown and described.

ROY V. DE VOY.
